UNITED STATES PATENT OFFICE.

JOHN WESLEY WOOD, OF MOBILE, ALABAMA.

CARBURETER.

No. 920,511.

Specification of Letters Patent.

Patented May 4, 1909.

Application filed October 24, 1908. Serial No. 459,396.

To all whom it may concern:

Be it known that I, JOHN WESLEY WOOD, a citizen of the United States, residing at Mobile, in the county of Mobile and State of Alabama, have invented certain new and useful Improvements in Carbureters, of which the following is a specification, reference being had to the accompanying drawings.

This invention relates to improvements in carbureters and particularly to that class which are portable and adapted for supplying an illuminating fluid to lime light burners and the like.

The object of the invention is to provide an improved carbureter especially adapted for saturating oxygen with ether for use in a lime light burner.

With the above and other objects in view, the invention consists of the novel features of construction and the combination and arrangement of parts hereinafter fully described and claimed, and illustrated in the accompanying drawings, in which—

Figure 1 is a side elevation, with parts in section, of the improved carbureting apparatus; Fig. 2 is a horizontal section taken on the plane indicated by the line 2—2 in Fig. 1; and Fig. 3 is a detail section taken on the plane indicated by the line 4—4 in Fig. 2.

In the drawings 1 denotes a lime light burner or its equivalent, 2 an oxygen tank and 3 the improved hydro-ether saturator or carbureter. The tank 2 has a suitable outlet valve 4 at its top and it is detachably connected by a coupling or connection 5 to one end of a gas supply pipe 6. A suitable pressure gage 7 is connected to the pipe intermediate its ends and also included in said pipe is an outlet or T-connection 8 containing a suitable needle valve 9 which controls the passage of oxygen through a flexible tube or pipe 10 from the pipe 6 to the burner 1. The other end of the supply pipe 6 is detachably connected by a coupling or connection 11 to a T-connection 12 having a branch 13 extending into the saturator 3 and containing a needle valve 14 for controlling the passage of oxygen gas from the pipe 6 to the branch or pipe 13.

The saturator 3 comprises an inner hermetically sealed body 15 preferably of cylindrical form and constructed of tin or other sheet metal coated with copper, and it also comprises an outer cylindrical jacket 16 which surrounds the body and is formed with perforations 17. Said jacket is preferably

constructed of nickel plated brass or equivalent material which will protect the body 1 and give a neat appearance to the generator, and also allow ventilation of the body and keep the latter cool. The branch 13 of the connection 12 is in the form of a small tube extending centrally in the body 15 to a point adjacent to its lower end and discharging into a spreading head or box 18 which it supports. Said box is formed in its top with perforations 9 which will cause the oxygen to be spread or disseminated throughout the body 3. The latter is adapted to be packed with cotton, as shown at 20, and the ether is supplied to it through a screw connection 21 in its top.

Arranged in the upper portion of the body is an inverted cone-shaped basket 22 constructed of woven wire and adapted to provide a gas mixing chamber.

23 denotes a gage cock extending through the jacket 16 and opening into the body 15 at a point suitably distant from the bottom of the latter. An outlet pipe or connection 24 is provided in the top of the body 15 and contains a valve 25 for controlling the passage of gas from the saturator through a flexible tube or pipe 26 to the burner 1.

The operation of the invention is as follows: Ether is supplied to the body 16 of the saturator through the filling connection 21, and it is then connected to one end of the pipe 6 by means of the connection or coupling 11 while the oxygen tank 2 is connected to the other end of said pipe by the connection or coupling 5. To start the apparatus, the valve 4 is first opened, then the valve 25, and then the valve 14. The burner 1 is then lighted and the valve 9 is then opened slowly to secure the proper illumination from the burner or lamp 1. To turn the apparatus off, the valve 9 is first closed, then the valve 14, then the valve 25 and finally the valve 4.

Having thus described the invention what is claimed is:

1. The herein-described carbureter comprising a cylindrical sheet metal body, a cylindrical metal jacket surrounding the body to reinforce the same and perforated to permit of ventilation for the body, a valve controlled inlet connection at the top of the body, a pipe depending from said connection and extending downwardly through the body and having an open lower end terminating adjacent to the bottom of the body, a hollow

distributing head having a closed bottom and side wall and a perforated top, the latter also having a central opening to receive the lower end of said pipe, a foraminous cone-shaped 5 partition adjacent to the top of the body to provide a mixing chamber, a filling material in the body around the pipe and between the mixing head and the foraminous partition, means at the top of the body for introducing a liquid therein, a valve 10 controlled outlet at the top of the body, a gage cock tapped through the jacket and body adjacent to the lower end of the latter, 15 a tank, a valve controlled outlet connection at the top of the same, a pipe, a coupling between one end of the latter and said valve connection of the tank, a T-connection in the last mentioned pipe, a valve in said T-connection, 20 a burner, a tube connecting the burner to said valve in the T-connection, a coupling between the other end of the last mentioned pipe and the valve-controlled inlet connection at the top of the body of the carbureter and a tube connecting the burner and the valve controlled outlet for the body of the carbureter.

2. The hereindescribed carbureter comprising a body, a jacket surrounding the body to reinforce the same and perforated to permit of ventilation for the body, a valve controlled inlet connection at the top of the body, a pipe depending from said connection and extending downwardly through the bottom and having an open lower end terminating adjacent to the bottom of the body, a hollow distributing head having a closed bottom and side wall and a perforated top, the latter also having a central opening to receive the lower end of said pipe, a foraminous cone-shaped partition adjacent to the

top of the body to provide a mixing chamber, a filling material in the body around the pipe and between the mixing head and the foraminous partition, means at the top of the body for introducing a liquid therein, a valve controlled outlet at the top of the body, a gage cock tapped through the jacket and body adjacent to the lower end of the latter, 30 a tank, a valve controlled outlet connection at the top of the same, a pipe, a coupling between one end of the latter and said valve connection of the tank, a T-connection in the last mentioned pipe, a valve in said T-connection, 35 a burner, a tube connecting the burner to said valve in the T-connection, a coupling between the other end of the last mentioned pipe and the valve-controlled inlet connection at the top of the body of the carbureter and a tube connecting the burner and the valve controlled outlet for the body of the carbureter.

In testimony whereof I hereunto affix my signature in the presence of two witnesses.

JOHN WESLEY WOOD.
